COMPRESSOR UNLOADING MECHANISM

Filed Jan. 14, 1921

Fig. 1.

Fig. 2.

UNITED STATES PATENT OFFICE.

WADE H. WINEMAN, OF CHICAGO, ILLINOIS, ASSIGNOR TO SULLIVAN MACHINERY COMPANY, A CORPORATION OF MASSACHUSETTS.

COMPRESSOR-UNLOADING MECHANISM.

Application filed January 14, 1921. Serial No. 437,235.

My invention relates to compressor unloading mechanisms.

An object of my invention is to provide an improved compressor unloading mechanism. Another object of my invention is to provide improved compressor unloading mechanism of the type adapted for the control of intake unloading valves. A further object of my invention is to provide an improved compressor unloading mechanism controlled by receiver pressure and operating without the expenditure of the compressed medium for effecting the necessary movements of the unloader. Other objects of my invention will appear in the course of the following specification and the appended claims.

In the accompanying drawings I have shown for purposes of illustration one embodiment which my invention may assume in practice.

In these drawings,

Fig. 1 is a side elevation, partially broken away, of a compressor plant provided with my improved unloading mechanism.

Fig. 2 is a vertical section taken on line 2-2 of Fig. 1 through the illustrative form of my unloading mechanism showing details of construction, certain parts being shown in elevation to facilitate illustration.

For purposes of illustration, I have shown my improved compressor unloading mechanism employed in combination with a compressor 1, having a cylinder 2 in which is reciprocable a piston 3, said piston serving to cause entrance of air to the compressor cylinder through an intake 4 controlled by an intake control valve 5 of the balanced type and discharging compressed air through a discharge chest 6 and pipe line 7 to a receiver 8. For the purpose of controlling the operation of the intake controlling valve 5, I have provided an improved means, as herein illustrated, comprising a valve stem 9 operative to raise and lower the valve 5, thereby opening and closing the latter, said valve stem 9 being controlled by a piston 10 movable in a cylinder 11 which communicates at its upper end with an enlarged clearance chamber 12. The clearance chamber communicates by way of a pipe 13 with the line 14 which connects the compressor intake proper with the intake controlling valve 5. By reason of this connection, variations in pressure occasioned

by the open and closed positions of the valve 5 may be transmitted to the chamber 12. The piston 10 is provided about its periphery with an annular groove 15 having a shoulder 15' arranged at a slight angle to the horizontal.

For the purpose of controlling the movements of the piston 10, I provide controlling means herein illustrated as comprising a diaphragm 16 mounted in a casing 17 and subjected to receiver pressure through a line 18 leading to the receiver. A heavy spring 19 is arranged between an adjustable abutment block 20 and a head 21 which presses upon the lower side of the diaphragm and tends to resist downward movement of the diaphragm under receiver pressure. Movable with the head 21 is a stem 22, to which are adjustably secured spacially separated nuts 23 and 24, these nuts being adapted to cooperate respectively with bell cranks 25 and 26 so located with respect to the cylinder 11 that one arm of the bell crank 25 may engage the shoulder 15' when the piston is in the position which it occupies when the valve 5 is closed and so that an arm of the bell crank 26 may engage the lower end of the piston 10 when the piston is raised to a position corresponding to "full-open" of the valve 5. It will be noted that a spring 27 extends between the bell cranks 25 and 26 and this spring is designed to maintain them with the piston engaging arms always in position to engage the notch in the piston or the lower end of the piston, when possible. An opening 28 is provided through the wall of the cylinder 11 to permit the bell cranks 25 and 26 to engage the piston 10.

From the foregoing description, taken in connection with the drawings, the mode of operation of my improved unloading mechanism will be readily apparent. When the compressor is operating to compress fluid, the intake valve 5 will be open and accordingly pressure substantially equal to atmospheric pressure will prevail in the clearance chamber 12. During this time, the spring 19 will hold the diaphragm 16 in raised position and will maintain the stem 22 in raised position, thereby removing the pressure of the nut 24 from the bell crank 26, whereby the spring 27 may hold one arm of that bell crank in engagement with the piston 10 and so hold the latter in elevated position.

Upon the receiver pressure's exceeding a predetermined desired amount, it will overcome the pressure of the spring and force down the diaphragm and the stem 22, causing the nut 24 to engage the bell crank 26 and release the piston 10 which will then fall by gravity closing the intake valve. The nut 23 having been moved downward will release the bell crank 25 which, under the action of the spring 27, will move so that its arm projecting into the cylinder 11 will engage in the groove 15 and cooperating with the shoulder 15' prevent upward movement of the piston 10. In view of the fact that the valve 5 is closed, a vacuum will be produced in the clearance chamber 12 so that upon fall in receiver pressure and the raising of the stem 22 as a result thereof, whereby release of the engagement of the bell crank 25 with the shoulder 15' is effected, the piston 10 will be forced upward by atmospheric pressure acting upon its lower end through the open end of the cylinder 11. It will be understood that the pipe line 13 is of a relatively small diameter so that pressure changes occurring in the intake of the compressor may not be absolutely instantaneously transmitted with full effect to the clearance chamber 12, i. e. so that the vacuum in chamber 12 may endure long enough to raise the piston 10.

From the foregoing description, it will be noted that I have provided an improved unloading mechanism in which no compressed fluid is requisite to effect operation of the actuating mechanism and in which the control by receiver pressure is effected by the condition in the intake of the compressor.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:—

1. A compressor unloading mechanism comprising, in combination, a valve controlling the intake of a compressor, and means operated by fluid pressure to move said valve to open position, including a member having a surface exposed constantly to a pressure which varies solely as a result of changes in position of said valve.

2. A compressor unloading mechanism comprising, in combination, a valve controlling the intake of a compressor, and means controlled by the pressure conditions in the compressor intake resulting from movement of said valve for causing movement of said valve.

3. In a compressor controlling mechanism, a valve operative when held in one position

to unload a compressor, and actuating means for said valve including an element constantly subject, on its opposite sides, to atmospheric pressure and pressure in the compressor at a point beyond said valve.

4. In a compressor controlling mechanism, a valve operative when held in one position to unload a compressor, and actuating means for said valve including an element constantly subject, on its opposite sides, to pressure in the compressor at a point beyond said valve and to a pressure which exceeds the minimum value of said first mentioned pressure.

5. In a compressor controlling mechanism, an intake closure valve, and operating means therefor including compressor discharge pressure controlled means and means governed thereby responsive to vacuum conditions resulting from closure of said valve.

6. In a compressor controlling mechanism, a valve whose actuation controls the loading of a compressor, pressure responsive means for actuating said valve, and fluid pressure controlled means for mechanically controlling the movement of said first mentioned means.

7. In a compressor controlling mechanism, a valve whose actuation controls the loading of a compressor, pressure responsive means for actuating said valve, and a fluid pressure controlled locking mechanism governing the instant of movement of said actuating means.

8. A compressor controlling mechanism comprising, in combination, a valve controlling a compressor intake, a piston controlling the position of said valve, means for transmitting to said piston the pressure variations in the intake of the compressor at a point beyond said valve, and means for controlling the response of said piston to said pressure variations, said last mentioned means being responsive to receiver pressure.

9. A compressor controlling mechanism comprising, in combination, a valve operative when in one position to effect unloading of a compressor, means responsive to fluid pressure for varying the position of said valve, means for transmitting fluid pressure variations resulting from unloading said compressor to said valve position varying means, and means cooperating with said valve position varying means to control the response of the latter to said fluid pressure variations.

10. In combination with a compressor discharging to a receiver, a compressor unloading mechanism comprising an intake controlling unloader valve, fluid pressure means for operating said valve, means for transmitting fluid pressure variations resulting from the closure of said valve to said last mentioned means, and means responsive to receiver

- pressure variations for mechanically controlling the operation of said valve.
11. A compressor unloading mechanism comprising, in combination, a valve controlling the intake of a compressor, and means for moving said valve including a member having a single surface exposed to variable pressure, said surface being exposed constantly to pressure variations arising solely from closure and opening of said valve.
12. In a compressor controlling mechanism, an element movable to effect unloading and loading of a compressor, means for moving said element exerting a force thereon tending to move the same, and compressor discharge pressure controlled means for preventing actuation of said element by said means except at a predetermined maximum desired compressor discharge pressure.
13. In a compressor controlling mechanism, an element movable to effect unloading and loading of a compressor, means for moving said element adapted alternately to exert forces to move the same in opposite directions, and compressor discharge pressure controlled means for mechanically preventing actuation of said element by said forces in either direction except at a predetermined compressor discharge pressure.
14. In a compressor controlling mechanism, an element movable to cause loading and unloading of the compressor, means operative to cause opposite movements of said element, and compressor discharge pressure controlled means including a member movable in opposite directions as compressor dis-
- charge pressure varies and mechanically controlling the actuation of said element by said means.
15. A compressor controlling mechanism including a valve operative when open to load a compressor and when closed to unload the same, a member operatively connected with said valve and movable to different positions to open and close said valve, and multi-latch means cooperating with said member to lock it in said different positions and movable to release said member, said means being governed by compressor discharge pressure.
16. A compressor controlling mechanism including a valve operative when open to load a compressor and when closed to unload the same, a member operatively connected with said valve and movable to different positions to open and close said valve, said member being acted on by an unbalanced force tending to move it to its opposite position substantially as soon as it reaches either position, and multi-latch means cooperating with said member to lock it in said different positions and movable to release said member, said means being governed by compressor discharge pressure.
17. The method of loading a motor compressor unit, which comprises controlling the loading pneumatically as a function of the suction caused by a drop of pressure in the inlet passages of the compressor.

In testimony whereof I affix my signature.

WADE H. WINEMAN.
